SAFETY RAZOR

Filed Nov. 16, 1929

Inventor:

Braddock Taylor

By Maria S. Cayer Atty.

UNITED STATES PATENT OFFICE

BRADDOCK TAYLOR, OF CHICAGO, ILLINOIS

SAFETY RAZOR

Application filed November 16, 1929. Serial No. 407,622.

The invention relates to safety razors, and more particularly to a device of this class comprising a blade carrier adapted to have a removable blade mounted thereon, a blade 5 clamping member removably associated with the carrier and serving to secure the blade in place, and a guard for the blade, the guard performing no function in holding the blade.

The main object of the invention is to provide a safety razor of the character described, the blade of which may be removably secured in position on the razor handle in such a manner as to permit the stropping or honing of the blade without necessitating the removal 15 of the same from the handle, whereby the use of special stropping appliances or attachments is avoided.

Another object of the invention is to provide a safety razor of the character described, 20 the blade of which may be removably secured in position on the razor handle by means of a novel and improved clamping member, said clamping member being so constructed that both edges of the blade may be honed or 25 stropped without any adjustment or changing of the parts other than the removal of the guard.

A further object of the invention is to provide a safety razor of the character described 30 which will simulate as closely as possible, the effect and mode of manipulation, both in shaving and stropping, of a straight blade integral shank razor, and which shall, at the same time, embody the feature of having a 35 double edge so that it may be used either right-handed or left-handed without changing the position of the guard, and in which the guard performs no function in holding the blade.

A still further object of the invention is to 40 provide a simple, strong and durable safety razor by means of which the operation of shaving can be expeditiously and comfortably executed, in which the parts are releasably associated so that the device can be 45 readily assembled and disassembled, which may be employed with a handle such as customarily associated with the ordinary razor, and which may be stropped or honed without 50 the use of special appliances or attachments,

and while in operative position on said handle.

With the foregoing and other objects in view, which will appear as the description proceeds, the invention consists in certain novel and improved features of construction, arrangements, and combination of parts, hereinafter more fully described, illustrated in the accompanying drawings, and particularly pointed out in the appended claims, it being understood that various changes in the form, and minor details of the structure may be made without departing from the spirit or sacrificing any of the advantages of the invention.

Stated generally, the invention comprises a blade holder consisting of two counter-part members, between which the blade is rigidly clamped with its cutting edges protruding on opposite sides of the holder in position not only for shaving with either edge, at will, but also to expose both faces of the blade adjacent to each edge in position for stropping. A guard of the usual toothed or serrated form is provided for releasable attachment with the holder, said guard fitting neatly upon the holder in guarding relation to both edges of the blade, but does not perform any function in holding the blade, thus when the guard is removed the said device may be manipulated 70 both in the operation of shaving and stropping, the same as a straight-blade integral shank razor.

For the purpose of facilitating an understanding of my invention, I have illustrated in the accompanying drawings a perfected embodiment thereof, from an inspection of which, when considered in connection with the following description, my invention, its mode of construction, assembly, and many of its advantages should be readily understood and appreciated.

Referring to the drawings, in which similar characters of reference are employed to indicate corresponding or similar parts throughout the several figures in the drawings:—

Fig. 1 is a top plan view of an embodiment of my invention, illustrating the device in 100 fully assembled position;

Fig. 2 is a bottom plan view of the same; Fig. 3, is a cross sectional view of the same taken on line 3—3 of Fig. 1;

Fig. 4 is a view in perspective of the blade clamping member with the blade shown thereon in dotted lines;

Fig. 5, is a view in perspective of the body of the blade carrier; and

Fig. 6, is a view in perspective of the guard member.

Referring more particularly to the drawings, the reference character 10, designates a blade carrier, which may be of suitable width, and terminates at one end in a shank 11, which is pivotally mounted by means of the rivet 12, or the like, between the sides 13, of a handle. As clearly shown in Fig. 5, of the drawings, one side of the blade carrier is substantially flat, and is adapted to receive thereagainst the face of the blade, whereas, the back face of said carrier may be slightly concave. The carrier 10, is provided intermediate the ends thereof with a pair of spaced openings, 14, and 15, said openings being substantially rectangular. A portion of the concave face of the carrier 10, adjacent each opening is cut away to form the undercut or countersunk ledges 16, and 17, each of which ledges has formed therein a small depression 18, substantially in the central portion thereof. The construction of the blade carrier so far described is the same as that disclosed in Patent No. 1,007,898, dated November 7, 1911, to T. C. Sheehan, and per se forms no part of the present invention.

A blade 19, having a longitudinal slot 20, therein, is adapted to be positioned on the flat surface of the blade carrier 10, said slot 20, being of sufficient length to permit the passage therethrough when the blade is in operative position on the carrier, of a pair of resilient offset lugs 21, and 22, provided on a blade clamping member 23, which member is of substantially the same width as the blade carrier 10. The lugs 21, and 22, are adapted when in operative position on the blade carrier, to frictionally engage the ledges 16, and 17, respectively, for clamping the blade 19, securely between the said members. The underside of each of the lugs is provided with a projection 24, which is adapted for engagement within its cooperating indentation 18, provided in the ledges, whereby displacement of the members 10, and 23, is prevented.

The resiliency of the offset lugs causes a firm locking engagement of the blade carrier and blade clamping member, with the blade therebetween, and when so locked the edges of the blade 19, extend beyond both the blade carrier and the clamping member, both of which members are of the same width. The razor may thus be readily stropped or honed, and may if so desired, be used as a simple razor without a safety guard.

In order to remove the clamping member 23, from operative engagement with the blade carrier, so that the parts may be disassembled for cleaning of the blade, or other purposes, the member 23, is slid forwardly so that the offset lugs 21, and 22, are moved out of engagement with their corresponding ledges, the said member 23, may then be dropped out of engagement with the carrier, the said lugs passing through the openings 14, and 15.

When it is desired to utilize the razor of the present invention as a safety razor, a suitable guard 25, is added to the assembly of the parts previously described. The guard 25, is adapted for quick and ready attachment to the blade carrier 10, which blade carrier may be readily modified in construction to adapt it for the attachment of the guard. The guard 25, is provided at its forward extremity with a hooked tongue 26, which is adapted when in operative position on the blade carrier 10, to engage within a cooperating groove or recess 27, formed in the upper side of the carrier 10, at the forward end thereof. At the rear extremity, the guard is provided with an offset lug 28, which is adapted to pass through a catch opening 29, similar to the opening 14, said opening 29, being provided in the shank portion 11, of the carrier, which portion is also provided on the rear face thereof, with a countersunk ledge 30, immediately adjacent the opening 29, said ledge being adapted for frictional engagement by the offset lug 28, which is of sufficient resiliency to securely lock the guard in place on the carrier.

In order to prevent the displacement of the guard, when the latter is in operative position on the carrier, I provide a depression 31, in the ledge 30, which indentation is adapted for receiving therein the projection 32, provided on the underside of the offset lug 28, said depression and projection cooperating to prevent the displacement of the guard member. The guard 25, is provided on the opposite longitudinal edges thereof, with the usual guard serrations or teeth 33, which teeth are adapted to extend over the cutting edges of the blade, as clearly shown in Figure 1, of the drawings. In order that the guard 25, may be readily removed from the carrier, it is provided with an upturned thumb piece 34, against which pressure may be exerted to slide the guard forwardly out of its engaging position until the offset lug 28, is permitted to pass through the catch opening 29.

It is to be noted that the guard of the razor is entirely an added member, and that it performs no function in the razor assembly other than that of a mere guard, the blade being held entirely by the carrier and the clamping member. The guard may thus be removed and leave the blade firmly secured in position on the blade carrier, and when in such position the blade of the razor may be stropped.

or honed without making it necessary to employ a special stropping handle or a special stropping appliance or attachment. In shaving, the guard may thus be readily removed and the blade conveniently stropped on the ordinary strop. It will also be noted that by merely providing the recess 27, and the catch opening 29, and ledge 30, in the blade carrier of the patent to Sheehan, No. 10 1,007,898, the said blade carrier is adapted for use with the guard 25, of the present invention.

15 The clamping member 23, and guard 25, may be constructed of any material found suitable in use. It is preferable, however, that such parts be stamped from metal because of manufacturing economy, and to secure the requisite resiliency and durability of the parts.

20 It is believed that my invention, its mode of construction, and many of its advantages should be readily understood from the foregoing without further description, and should be also manifest that while a preferred embodiment of the invention has been shown and described for illustrative purposes, the structural details are nevertheless capable of wide variation within the purview of my invention, as defined in the appended claims.

25 30 What I claim and desire to secure by Letters Patent of the United States is:—

1. In a razor, the combination with a blade carrier member, of a blade clamping member formed of sheet metal and being of substantially the same width as the blade carrier, an offset lug on said clamping member adapted to engage the carrier member to clamp a blade between the members, a notch formed on said carrier member at one end thereof, a slot formed in said carrier member at the other end thereof, a ledge formed adjacent said slot, and an independently removable guard member having a hook arranged to engage in the said notch in said carrier member, and an offset lug provided on said guard member adapted to engage the ledge after passing through the said slot for securely holding the said guard in place on said carrier member.

35 40 45 50 55 60 65 2. A safety razor, comprising a blade carrier adapted to support a blade, a blade holder of substantially the same width as the blade carrier having a removable connection with said carrier, and provided with means for securing the blade in place, and a blade guard extending over said holder and having means for releasable attachment to said carrier, said means comprising a notch formed in said carrier at one end thereof, a hook portion formed at one end of said guard member and adapted to be received in said notch and an offset lug formed at the other end of said guard member, adapted for engagement within a slot provided in the other end of said carrier member.

3. A safety razor, comprising a blade carrier member adapted to support a blade, a blade clamping member having a removable connection with said carrier member, and provided with means for securing the blade in place, a notch formed in said carrier member at one end thereof, and a slot formed in said carrier member at the other end thereof, a counter-sunk ledge formed adjacent said slot, said ledge being provided with an indentation, and an independently removable guard member formed of sheet metal and provided with a hook portion for engaging within said notch, and an offset lug provided with a projection adapted to engage the indentation of the said ledge.

4. A safety razor, comprising a blade carrier member adapted to support a blade, a blade clamping member having a removable connection with said carrier member, and provided with means for securing the blade in place, a notch formed in said carrier member at one end thereof, a slot and a counter-sunk ledge provided in said carrier member at the other end thereof, said ledge being provided with an indentation, and an independently removable guard member formed of sheet metal and provided with an integral resilient hook for engagement within said notch and an integral resilient offset lug having a projection adapted to engage the indentation on said ledge.

In testimony whereof I affix my signature.
